UNITED STATES PATENT OFFICE

163,394

TOY GUN HOLSTER FOR BICYCLES

Bernard Krasnow, Suffern, N. Y., assignor to Yale
Belt Corp., New York, N. Y., a corporation of
New York

Application July 7, 1950, Serial No. 10,996

Term of patent 14 years

(Cl. D34—15)

To all whom it may concern:

Be it known that I, Bernard Krasnow, a citizen of the United States of America, residing at the city of Suffern, county of Rockland, State of New York, have invented a new, original, and ornamental Design for a Toy Gun Holster for Bicycles, of which the following is a specification, reference being had to the accompanying drawing, forming part thereof.

In the drawing:

Fig. 1 is a side elevational view of a toy gun holster set for bicycles, showing my new design; Fig. 2 is a front elevational view thereof; and Fig. 3 is a top plan view thereof.

The side not shown has substantially the same appearance as the side shown in Fig. 1.

The straps of the bottom of Figs. 1 and 2 are broken away for convenience of illustration.

I claim:

The ornamental design for a toy gun holster for bicycles, substantially as shown and described.

BERNARD KRASNOW.
